CLAIM

The ornamental design for a hair barrette, as shown and described.

DESCRIPTION

FIG. 1 is a perspective view of a hair barrette showing
my new design;

FIG. 2 is a top plan view thereof;

FIG. 3 is a front elevational view thereof;

FIG. 4 is a bottom plan view thereof; and

FIG. 5 is a side elevation view thereof, with the barrette in a reversed position in relation to the clasp.

The broken line showing of the woman is for illustrative purposes only and forms no part of the claimed design.

FIG. 2FIG. 3*FIG. 4*FIG. 5
